UNITED STATES PATENT OFFICE.

GEORGE E. KRAEMER, OF CINCINNATI, OHIO.

ELECTRIC-CURRENT-CONTROL SWITCH.

Application filed November 3, 1925. Serial No. 66,650.

An object of my invention is to provide a mechanism for automatically illuminating the interior of an ice-box, telephone booth, or other compartment into which a person enters and closes the door thereof upon himself.

Another object is to provide a mechanism for a compartment which will close an electric circuit upon the opening of the door of said compartment, retaining the circuit in a closed position during the time that a person remains therein with the door in the closed position, and then break the circuit upon the closing of the door after exit of the person from the compartment.

Another object is to provide a device of such construction as to permit the utilization of standard fixtures which may be bought on the market.

A further object of my invention is to provide a device of a construction which permits ready replacement of broken or worn units thereof at low cost.

These and other objects are attained by the means described herein and disclosed in the accompanying drawings, in which:

Fig. 1 is a fragmental front view of a chamber or compartment such as an ice-box having embodied therein a device of my invention.

Fig. 2 is an enlarged sectional view on line 2—2 of Fig. 1.

Fig. 3 is a diagrammatic representation of the wiring and associated parts of the device of my invention in a normally inoperative position.

Fig. 4 is a similar view showing the relation of parts after a person has opened the door and entered the compartment, thereby closing the circuit and lighting the interior of the compartment.

Fig. 5 shows diagrammatically the device of my invention when a person has closed the door behind him on entering the compartment.

Fig. 6 shows diagrammatically the relation of parts assumed by the device when the door is opened a second time to permit exit of a person from the compartment or chamber.

Fig. 7 is a diagrammatic representation of a three point switch used in my device.

An ice-box 7 has the usual door 8, sash 9 and ceiling 10 and is provided interiorly with an electric lamp 11, which is wired in parallel with an indicator lamp 12 disposed

outside the ice-box at any convenient location. In ice-boxes provided with windows, the lamp 12 may be dispensed with as it merely indicates whether or not the light inside the ice-box is lit.

Secured to the sash 9 adjacent the door 8 are electric switches 13, 14 and 15, the switch 13 being of the momentary contact type and operated by an insulated push button 16. Depressing the button 16 as shown in Fig. 3, opens the switch. The switch is held closed by the compression of spring 17 within said switch, as shown in Fig. 4. Switches 14 and 15, operated by insulated push buttons 18 and 19 respectively, are preferably of the rotary action type, in which successive depressions of a push button will alternately open and close the circuit of that switch. These switches may be separate or combined in one casing, as desired. Secured to the door 8, by means of screws 20, are brackets 21 and 22 each of which carries a rubber covered or otherwise resilient roller 23 for engagement with the push buttons 16 and 19. Fig. 2 shows the preferred method for mounting the rollers, that is, on U-shaped members 24 secured to a horizontal face 25 of the bracket 22. Brackets 21 and 22 are similar. Obviously, the rollers 23 of brackets 21 and 22 contact the switch buttons 16 and 19 respectively only when the door is in the closed position. It should be noted that switches 14 and 26 normally retain the positions shown in Fig. 3. Switch 14 is inserted in the circuit merely to permit manually operated lighting in the event of the automatic means becoming inoperative due to breakage or the like. The function of switch 26 will be set forth later.

In using the automatic means, which is the means normally in operation on the device, the only switches that are actuated are the momentary contact switch 13 and the rotary switch 15. It should be noted that switch 13 is open while the door 8 is closed, as shown in Figs. 3 and 5, and upon opening of the door, the switch is closed by the action of spring 17, as shown in Figs. 4 and 6.

Referring to the diagrams, one lead-in wire 30 of the circuit has, in series, a lamp 12 or a plurality of lamps, and the movable contact 37 of the three point rotary switch 15. The two fixed contacts 31 and 38 of switch 15 have shunted across them the mo-

momentary contact switch 13 in series with the single pole switch 14. It is the tendency of compression spring 17 to hold the reciprocable conductor 29 in engagement with contacts 27 and 28 of switch 13. The engagement of roller 23 on bracket 21 with the push button 16, however, holds the switch in an open position when the door is closed, as shown by Figs. 3 and 5. A three point switch 26, used for manually operating the lights 11 and 12 has its two fixed contacts 32 and 40 electrically connected to the two fixed contacts 31 and 38 respectively of switch 15. The purpose of such connection is to selectively close a circuit through either of the contacts 31 and 38 of switch 15.

From the foregoing, it will be apparent that in Fig. 3, the door is closed and no current may pass over main line 30, through lamps 11 and 12, then to contacts 37 and 38 of switch 15, and through the shunt circuit to line 33, because the shunt circuit across terminals 31 and 38 is open at switch 13, due to the door being in a closed position neither will the current pass through contact 37 to 38 and then over conductor 41 to terminal 40 of switch 26, as terminal 40 is not connected to main line 33. Therefore, the lamps 11 and 12 will not burn.

In Fig. 4 the door 8 has been opened and roller 23 secured thereto leaves switch 13, allowing spring 17 to actuate the switch for closing the circuit of the shunt. Here, current coming over conductor 30, passes through lights 11 and 12 to contact 37, and since conductor 41 is open at 40, the current follows the path through contact 38, switch 13, switch 14, contact 31, over conductor 42 to contact 32 of switch 26 and thence through movable contact 43 to main line 33, thus completing the circuit and lighting the lamps.

Similarly in Fig. 5, wherein it is assumed that a person has entered and enclosed himself within the ice box, current upon reaching movable contact 37, which has been moved by closing of the door, to engage contact 31, passes over conductor 42 to the fixed contact 32 of switch 26 and then to contact 43 to complete the circuit. It should be noted that in this operation, the switch 13 again opens the shunt circuit and no current flows therethrough, but nevertheless the circuit is closed by passing of current over wire or conductor 42 and the lamps continue to burn.

In Fig. 6 the assumption is that the person within desires to leave the ice box and has opened the door. The contact 37 of switch 15 has not moved because on opening of the door 8 there is no depression of the push button 19. Depression of said push button is caused only by closing of the door. Current reaching movable contact 37, as in the foregoing explanations, passes through

contact 31, conductor 42 to terminal 32 of switch 26, through contact 43 to main line 33, thus retaining the lamps in a closed circuit wherefore they continue to burn until the door is again closed and the parts are returned to the positions and relations indicated in Fig. 3.

The operation of the device is as follows:

The device is assumed to be installed on the ice box of a meat market, and a person wishes to enter the ice box and remove objects therefrom. Under the above assumption, the door will be in the position shown in Figs. 1 and 2, and Fig. 3 will represent the relative positions of the switches and door. It should be noted that due to the relative positions of switches 13 and 26, current cannot flow and consequently the lights 11 and 12 will not burn. The man now opens the door to enter the ice-box, and immediately upon slightly opening it, switch 13 closes the circuit as shown by Fig. 4, and current is allowed to flow through the switches 13, 14 and 26, and cause the lights 11 and 12 to burn. Having opened the door and entered the ice box, the man now closes the door behind him and attends to his work inside the ice box. The relation of the parts is shown now by Fig. 5. It should be noted that upon closing of the door, roller 23 actuated switch 15 for connecting the line 30 with the third contact 31 of the switch 15, which leads directly to the terminal 32 of switch 26, which communicates with main line 33, thus retaining the circuit in a closed condition and causing the lights to continue burning. The man inside the ice box now opens the door to leave the ice box, and the various parts assume the positions shown in Fig. 6, wherein switch 13 closes, due to the action of spring 17 operating while the door is open. The circuit is still closed, and the lamps remain lighted until finally closing door 8, whereupon the condition shown by Fig. 3 again exists.

As disclosed therein, switch 15 has operated to move from the position shown in Fig. 6 to that shown in Fig. 3, and the momentary contact switch 13 has opened by reason of the closing of the door and consequent contact of the roller 23 with the push button 16. The lights are therefore extinguished. It is thus seen that a person entering an ice box, telephone booth, or the like is provided with light while he is inside such compartment, and also that said compartment is without light while not in use. Thus a saving of much current is effected, especially where a plurality of lights is used. Furthermore, the heat radiated by some lamps is very undesirable, as in an ice box or in a very small compartment.

In the event that a person is within an ice box and a second person wishes to enter, it becomes necessary to change the sequence of the various operations of the switches,

which is readily accomplished by actuation of the three point switch 26 by the second person. For example, a person is within the box, and therefore the diagram of Fig. 5 represents the relation of the parts. Now, should a second person open the door and enter, the condition represented in Fig. 6 would exist, and subsequent closing of the door by such second person behind him would leave both persons in the ice box, in darkness, as shown by Fig. 3.

To overcome this, a simple method is employed. The second person, seeing that the indicator lamp 12 is lit, knows that some one is in the ice box. Fig. 5 represents the condition now assumed. He thereupon opens door 8 and switch 13 automatically closes. There is then current flowing through both wires 41 and 42, leading to switch 26, and therefore such second person can throw switch 26 to the position shown by dotted line 36, and thus change the sequence of operation.

Switch 14 is provided for cutting out the automatic means in the event that switch 15 should become defective in either of the positions shown in Figs. 4 and 5, as by the breakage of a spring or the like. In such case, the lights could be operated manually by switch 23 as has been done heretofore.

Fig. 7 is a representation of the type of three point switch which may be used in the device of my invention. Referring to Figs. 3 and 7, corresponding numerals designate corresponding parts of the switches. Contacts 31 and 38 are fixed, and contact 37 is adapted for rotation about a pin 39. It is readily apparent that a quarter turn of the movable contact 37 will connect it with contact 38, and successive quarter turns will alternately connect it with contacts 31 and 38. The contact 37 is rotated preferably by a single push button arrangement, not shown.

Since all the switches used are of standard manufacture, they can be very readily replaced with little effort upon becoming worn or broken.

The switch shown in Fig. 6 and connected with conductor 42 and the upper conductor 50 between lamps 11 and 12 and switch 15, is provided to permit manual control of the lamps 11 and 12 if for any reason there should be any occasion therefor.

What I claim is:

1. The combination of an electrical circuit comprising a source of electrical energy, an electrical element electrically connected with the source of electrical energy, a three point switch comprising a movable contact point, said movable contact point being electrically connected with the electrical element, a normally inoperative second switch shunted across the second and third contact points of said three point switch, the second switch being connected with the source of electrical supply, and an actuating device for actuating the three point switch and the said second switch whereby the actuating device successively actuates the movable contact point of the three point switch between the second and third contact points thereof and also actuates the said second mentioned switch for causing said second switch to assume an operative position with each operation of the actuating device. 75

2. The combination of an electrical circuit comprising a source of electrical energy, an electrical element electrically connected with the source of electrical energy, a three point switch comprising a movable contact point, said movable contact point being electrically connected with the electrical element, a normally inoperative second switch shunted across the second and third contact points of said three point switch, the second switch being connected with the source of electrical supply, and an actuating device for actuating the three point switch and the said second switch whereby the actuating device successively actuates the movable contact point of the three point switch between the second and third contact points thereof and also actuates the said second mentioned switch for causing said second switch to assume an operative position with each operation of the actuating device. 80

3. The combination with an enclosed chamber having a door, of an electrical circuit extending into the chamber and comprising an electrical element within the chamber, a three point switch, a double section of wiring, each wire of said double section being connected with an individual point or contact of the switch and arranged for selective connection with the third point of the switch, a switch shunted across the double section of wiring for co-operation with the three point switch for making and breaking the circuit through the electrical element, and switch actuating means operative upon closing of the door for actuating the first switch and for holding the second switch in open position. 85

4. The combination with an enclosed chamber having a door, of an electrical circuit extending into the chamber and comprising an electrical element within the chamber, a three point switch, a double section of wiring, each wire of said double section being connected with an individual point or contact of the switch and arranged for selective connection with the third point of the switch, a switch shunted across the double section of wiring for co-operation with the three point switch for making and breaking the circuit through the electrical element, and switch actuating means associated with the door for 90

5. The combination with an enclosed chamber having a door, of an electrical circuit extending into the chamber and comprising an electrical element within the chamber, a three point switch, a double section of wiring, each wire of said double section being connected with an individual point or contact of the switch and arranged for selective connection with the third point of the switch, a switch shunted across the double section of wiring for co-operation with the three point switch for making and breaking the circuit through the electrical element, and switch actuating means associated with the door for 95

6. The combination with an enclosed chamber having a door, of an electrical circuit extending into the chamber and comprising an electrical element within the chamber, a three point switch, a double section of wiring, each wire of said double section being connected with an individual point or contact of the switch and arranged for selective connection with the third point of the switch, a switch shunted across the double section of wiring for co-operation with the three point switch for making and breaking the circuit through the electrical element, and switch actuating means associated with the door for 100

7. The combination with an enclosed chamber having a door, of an electrical circuit extending into the chamber and comprising an electrical element within the chamber, a three point switch, a double section of wiring, each wire of said double section being connected with an individual point or contact of the switch and arranged for selective connection with the third point of the switch, a switch shunted across the double section of wiring for co-operation with the three point switch for making and breaking the circuit through the electrical element, and switch actuating means associated with the door for 105

8. The combination with an enclosed chamber having a door, of an electrical circuit extending into the chamber and comprising an electrical element within the chamber, a three point switch, a double section of wiring, each wire of said double section being connected with an individual point or contact of the switch and arranged for selective connection with the third point of the switch, a switch shunted across the double section of wiring for co-operation with the three point switch for making and breaking the circuit through the electrical element, and switch actuating means associated with the door for 110

9. The combination with an enclosed chamber having a door, of an electrical circuit extending into the chamber and comprising an electrical element within the chamber, a three point switch, a double section of wiring, each wire of said double section being connected with an individual point or contact of the switch and arranged for selective connection with the third point of the switch, a switch shunted across the double section of wiring for co-operation with the three point switch for making and breaking the circuit through the electrical element, and switch actuating means associated with the door for 115

10. The combination with an enclosed chamber having a door, of an electrical circuit extending into the chamber and comprising an electrical element within the chamber, a three point switch, a double section of wiring, each wire of said double section being connected with an individual point or contact of the switch and arranged for selective connection with the third point of the switch, a switch shunted across the double section of wiring for co-operation with the three point switch for making and breaking the circuit through the electrical element, and switch actuating means associated with the door for 120

11. The combination with an enclosed chamber having a door, of an electrical circuit extending into the chamber and comprising an electrical element within the chamber, a three point switch, a double section of wiring, each wire of said double section being connected with an individual point or contact of the switch and arranged for selective connection with the third point of the switch, a switch shunted across the double section of wiring for co-operation with the three point switch for making and breaking the circuit through the electrical element, and switch actuating means associated with the door for 125

12. The combination with an enclosed chamber having a door, of an electrical circuit extending into the chamber and comprising an electrical element within the chamber, a three point switch, a double section of wiring, each wire of said double section being connected with an individual point or contact of the switch and arranged for selective connection with the third point of the switch, a switch shunted across the double section of wiring for co-operation with the three point switch for making and breaking the circuit through the electrical element, and switch actuating means associated with the door for 130

actuating the switches, and a means co-operative with the double section of wiring for changing the sequence of the making and breaking of the circuit.

5. The combination with an enclosed chamber having a door, of an electrical circuit extending into the chamber and comprising an electrical element within the chamber, a three point switch, a double section of wiring, each wire of said double section being connected with an individual point or contact of the switch and arranged for selective connection with the third point of the switch, a switch shunted across the double section of wiring for co-operation with the three point switch for making and breaking the circuit through the electrical element, means associated with the door for actuating the switches, and means for opening and closing the circuit independently of the three point switch, the shunted switch and the means associated with the door for actuating the switches.
6. The combination with a chamber having a door controlling access thereto, of an electrical circuit extending into the chamber and comprising an electrical element within the chamber, a pair of three point switches electrically connected with said circuit and in series with the electrical element within the chamber, said electrical circuit comprising said pair of three point switches and a section of parallel wiring extending between the three point switches, a momentary contact switch adjacent the door and arranged for operation by the door, said momentary contact switch being connected across the section of parallel wiring connecting the pair of three point switches, the door adapted to operate one of the three point switches,

whereby the first movement of the door operates the momentary contact switch for connecting the parallel wiring, and the second movement of the door operates the one three point switch and breaks the connection through the momentary contact switch, the third movement of the door again completes the connection between the parallel wiring through the momentary switch, and the fourth movement of the door operates the said one three point switch and also actuates the momentary contact switch for again breaking the electrical connection through the momentary contact switch between the said parallel wiring.

7. The combination with an enclosed chamber having a door, of an electrical circuit extending into the chamber and comprising an electrical element within the chamber, a three point switch, a double section of wiring, each wire of said double section being connected with an individual point or contact of the switch and arranged for selective connection with the third point of the switch, a switch shunted across the double section of wiring for co-operation with the three point switch for making and breaking the circuit through the electrical element, switch actuating means operative upon closing of the door for actuating the first switch and for holding the second switch in open position, and means for changing the sequence of said making and breaking of the circuit through said electrical element.

In testimony whereof, I have hereunto subscribed my name this 31st day of October, 1925.

GEORGE E. KRAEMER.
